(57) **CLAIM**

The ornamental design for a tire tread, as shown and
described.

DESCRIPTION

FIG. 1 is a perspective view of a portion of a tire tread of our
new design, the back view, the top view and the bottom view
are all same images of the front view; and,

FIG. 2 is a front view thereof.

The broken line showings of the remainder of the tire are for
illustrative purposes only and form no part of the claimed
invention.
